UNITED STATES PATENT OFFICE.

MAURICIO L. NOVO, OF GUADALUPE, CALIFORNIA.

CULTIVATOR.

1,426,665.

Specification of Letters Patent. Patented Aug. 22, 1922.

Application filed August 12, 1921. Serial No. 491,771.

To all whom it may concern:

Be it known that I, MAURICIO L. Novo, citizen of the United States, residing at Guadalupe, in the county of Santa Barbara 5 and State of California, have invented certain new and useful Improvements in Cultivators, of which the following is a specification.

This invention relates to cultivators and 10 one object thereof is to provide a structure whereby the direction of travel of the cultivator may be reversed without turning the complete implement.

A further object of the invention is to 15 provide simple and efficient means whereby the gang of cultivating blades may be set at any desired angle.

And a further object of the invention is to 20 provide a cultivator of a strong and durable construction whereby the life of the implement will be prolonged and its efficiency increased.

The invention is illustrated in the accompanying drawings, wherein:

25 Figure 1 is a plan view of one embodiment of my invention,

Figure 2 is a central longitudinal section of the same,

Figure 3 is a transverse section on the 30 line 3—3 of Figure 1.

In carrying out my invention I employ a main frame consisting of angle bars 1 curved regularly from end to end so as to define semi-circular arcs. These frame 35 members are disposed in the same horizontal plane with their ends spaced apart as shown at 2, and are connected at their ends by braces 3 which are spaced inwardly from the vertical webs of the angle bars so 40 that the spaces 2 will be left open to admit a locking pin hereinafter described. Spaced inwardly from the connecting bars or members 3 are intermediate braces 4 which may conveniently be flat bars disposed on arcs of 45 the frame and having their ends rigidly secured to the horizontal webs of the frame bars 1 as will be readily understood. The frame bars are further connected upon their transverse radii by a beam 5 which 50 may conveniently be a flat metallic bar having its extremities turned downwardly as shown at 6 to be rigidly secured to the horizontal webs of the frame bars and support the intermediate portion of the beam above 55 said webs. The beam 5 is offset vertically at its center, as shown at 7, and upon the

said offset portion a tongue 8 is pivotally secured by a pivot bolt 9. As shown most clearly in Figures 1 and 2, the tongue extends unequal distances to the opposite sides 60 of the pivot and upon the shorter arm thereof I secure a seat standard 10 carrying a seat 11. The longer arm of the tongue projects over and beyond the frame bars 1 and at its outer extremity is provided with a 65 retaining plate or keeper 12 from the inner edge of which a fork or bracket 13 extends downwardly and rearwardly to engage under the adjacent frame bar 1, as shown most clearly in Figure 2. The tongue is thus 70 prevented from riding up from the frame in an obvious manner. A clevis 14 is secured to the outer extremity of the tongue and this clevis may be of any preferred construction and any desired form of draft 75 coupling 15 may be attached to the clevis and adjusted vertically thereon. In rear of the clevis, a longitudinal slot 16 is provided in the tongue and a locking pin or lever 17 is pivotally mounted upon the upper side of the tongue and has its lower end extended through the said slot and adapted to engage in either space 2 of the frame, and by its engagement with the sides of 80 said spaces, prevent relative movement of 85 the tongue and the frame. The tongue may conveniently be a channel bar, as illustrated, and the pivot of the locking lever or pin may be mounted in the vertical webs or ribs of the said channel bar. In rear of 90 the locking pin or lever, a bracket or abutment 18 is secured upon the tongue and a link 19 is extended through the said bracket or abutment and has its front end pivoted to the upper extremity of the locking pin 95 and at its rear end is pivoted to a hand lever 20 which is mounted upon the tongue in advance of the seat 11 where it may be conveniently reached by the driver. A spring 21 is coiled around the link 19 between the 100 abutment 18 and the locking pin and is normally extended so as to hold the locking pin in engagement with the space 2 between the opposed ends of the frame bars 1. A foot rest 22 is provided upon the tongue adjacent the hand lever and the driver's seat and it may be secured to the tongue by one of the bolts which secure the base portion 105 of the bracket 18 thereto.

To the connecting bars 3 and 4, I secure the upper ends of standards 23 in the lower ends of which is journaled a shaft 110

24 carrying discs, cutters or cultivator blades 25. In the illustrated embodiment of the invention, I have shown flat discs which are adapted to cut into the surface of the soil sufficiently to hold the cultivator to a rectilinear path. It is obvious, however, that the ordinary concave rolling cultivator discs may be employed, or harrow teeth, or other ground treating members may be 10 mounted upon the shaft or rod 24. Below the central transverse beam 5, I provide a cultivator beam consisting of angle bars 26 connected near one end by a coupling block 27 and supported eccentrically from the 15 beam 5 by a pivot bolt 28 inserted through the said block 27 and the said beam. At their ends and at their centers, the angle bars 26 are connected by the heads 29 of standards 30; the said heads being rigidly 20 secured to the horizontal webs of the angle bars, and a cultivator shaft 31 being rotatably mounted in the lower ends of the standards. The usual concave rolling cultivator discs 32 are fitted upon the shaft and 25 spacing sleeves 33 are mounted upon the shaft between the said discs so as to maintain the discs in fixed spaced relation. The beams 26, adjacent their ends more remote from the pivot 28, rest slidably upon a supporting arm or bar 34 which is secured to and extends between the intermediate connecting portions 4 and defines an arc having the pivot 28 as its center. The cultivator beam is thus pivotally supported 30 against dropping and may be set at any desired angle to the line of draft. In order that the gang of cultivator discs may be held in the position in which it is set, I provide the lugs 35 upon the standard 30 at that end of the gang remote from the pivot and to the said lugs I secure adjusting chains 36. Upon the connecting members or bars 4 I provide loops 37 having a keyhole slot formation and the free portions 40 of the said chains 36 extend through the said loops. If a link of a chain 36 be engaged in the reduced portion of the loop 37, the ends of the connected links will extend across said reduced portion of the loop and 45 thereby prevent movement of the chain through the same so that the chains will be held taut and the gang of cultivator discs held in the position in which it may be set. To shift the gang, the adjusting chain 36 is 50 released from the reduced portion of the keyhole slot in the loop or keeper 37 and may then be easily drawn through the larger portion of said loop as will be readily understood.

55 When the cultivator has been drawn to the end of a row or the side of a field, the driver swings the hand lever 20 rearwardly, thereby pivotally actuating the locking pin or lever 17 against the tension of the spring 21 and withdrawing the lower end of said

pin or lever from the notch or space 2 in the main frame. The team or the tractor may then be driven around the cultivator frame, causing the tongue to swing about its pivot 9 and assume a relatively reversed position, as indicated by the dotted lines in figure 2. The lever 20 may, of course, be released as soon as the locking pin has cleared the notch or recess 2 in which it was engaged and it will then ride around the outer side of the adjacent frame bar until it reaches the diametrically opposite space or notch 2 into which it will at once be projected by the expansion of the spring 21 in an obvious manner. It will thus be seen 80 that the cultivator may be quickly brought into position to make a return trip and the gang of cultivator blades or discs will automatically swing about its pivotal support when the return trip is started. It will be understood that, except when the gang of discs 32 is disposed in alignment with the beam 5, one of the chains 36 will be slack and the draft upon the gang will bring the 85 advance chain into a taut condition so that the discs will be set in the desired operating position. My improved cultivator may be produced at a low cost and its use will effect a pronounced saving of time in reversing the travel of the implement and adjusting the cultivator blades or discs to the 90 working position.

Having thus described the invention, what is claimed as new is:

1. In a cultivator, the combination of a circular main frame provided with notches in its outer edge at diametrically opposite points, a tongue pivotally mounted upon the frame at the center thereof and extending over the side of the same, a locking pin 100 mounted for vertical rocking movement upon the tongue and adapted at its lower end to engage either of said openings in the main frame, and means upon the tongue acting on the upper end of said locking pin 105 to set the same.

2. In a cultivator, the combination of a circular main frame provided with openings in its edge at diametrically opposite points, a tongue pivotally mounted upon the main frame at the center thereof, a locking pin carried by said tongue and adapted to engage either of said openings in the main frame, a bracket mounted upon the tongue at the inner side of said locking 115 pin, a hand lever mounted upon the tongue at the inner side of said bracket, a link connecting the hand lever and the locking pin and extending through said bracket, and a spring coiled around said link between the bracket and the locking pin.

3. In a cultivator, the combination of a circular main frame, a tongue pivotally mounted upon the frame at the center thereof and projecting over the side of the frame,

means upon the tongue to engage the frame and hold the tongue in an operative position, and a keeper carried by the outer end of the tongue and engaging under the side 5 of the main frame.

4. In a cultivator, the combination of a main frame, a gang of cultivator members pivotally supported eccentrically upon the main frame, and adjustable connections between the said gang of cultivator members 10 and the main frame to hold the said gang in a set angular position.

5. In a cultivator, the combination of a main frame, a gang of cultivating instruments pivotally connected at one 15 end with the main frame eccentric thereto, an arcuate supporting bar upon the main frame upon which the free end of the gang of cultivating instrumentalities is slidably supported, and adjustable connections be- 20

tween the latter end of the gang of cultivating instrumentalities and the main frame whereby to hold said gang in a set angular position.

6. In a cultivator, the combination of a 25 main frame, a beam pivoted adjacent one end upon the main frame eccentric thereto and having its opposite end slidably supported by the main frame, a gang of cultivating members carried by said beam, 30 slotted keepers upon the main frame at the opposite sides of the beam, said slotted keepers having reduced portions, and chains connected with the beam at the opposite sides of the same and at the free end thereof 35 and adapted to engage the said slotted keepers.

In testimony whereof I affix my signature.

MAURICIO L. NOVO. [L. s.]
